CHARGE DELIVERY ACTUATING MEANS FOR MOLDING MACHINES

Original Filed Dec. 14, 1922

Patented Sept. 1, 1925.

1,551,608

UNITED STATES PATENT OFFICE.

CHARLES L. NORTON, OF BOSTON, MASSACHUSETTS, ASSIGNOR TO REFRactories
MACHINERY MANUFACTURING COMPANY, OF PITTSBURGH, PENNSYLVANIA, A
CORPORATION OF PENNSYLVANIA.

CHARGE DELIVERY ACTUATING MEANS FOR MOLDING MACHINES.

Original application filed December 14, 1922, Serial No. 606,869. Divided and this application filed
October 13, 1924. Serial No. 743,191.

To all whom it may concern:

Be it known that I, CHARLES L. NORTON, a citizen of the United States of America, and resident of Boston, in the county of Suffolk and State of Massachusetts, have invented new and useful Improvements in Charge-Delivery Actuating Means for Molding Machines, of which the following is a specification.

- 10 This invention pertains to machines for molding shapes from fistic material wherein the charge of material is permitted to fall freely from a height into an open topped mold box to fill the latter, machines of this type being illustrated in my prior Patents No. 1,332,677, dated March 2, 1920 and No. 1,426,761, dated August 22, 1922, and relates more particularly to improved means for actuating the charge delivery devices.
- 15 As herein illustrated the improved charge delivery actuating means is shown as applied to a molding machine of the kind more fully disclosed in my co-pending application, Serial No. 606,869 filed December 14, 1922 which has resulted in Patent 1,524,877 of which this application is a division, but the improved actuating means herein claimed is of broad utility and not necessarily restricted to this particular environment.
- 20 In the accompanying drawings in which certain desirable embodiments of the invention are illustrated by way of example

Fig. 1 is a fragmentary front elevation of a molding machine showing the improved charge delivery actuating means applied thereto;

Fig. 2 is a fragmentary side elevation of the upper part of the machine frame showing further details of the improved actuating mechanism; and

Fig. 3 is a fragmentary front elevation illustrating a modified form of the actuating mechanism.

Referring to the drawings the numeral 1 designates a horizontally disposed anvil plate rigidly supported upon girders or I-beams 2. This anvil plate is preferably provided with one or more adjustable stops 3 constituting the support for the mold box 4 while the latter is being filled.

The mold box herein disclosed comprises the open topped box 4 which is provided with a telescopic bottom member or push

plate 5 which acts to eject the molded shape after the molding operation. The box proper and the bottom member 5 are held in proper assembled relation by means of a pin and slot connection.

The bottom member 5 of the mold box is supported by an arm 6 secured to an oscillatory shaft 7 mounted in suitable bearings in the machine frame. This shaft is also furnished with a segmental gear 8 which meshes with a rack bar 9 which is reciprocated by any suitable mechanism, for example, a piston operating in a pressure cylinder, such mechanism not being shown herein.

A second shaft 10 is arranged substantially parallel to the shaft 7 but at the opposite side of the anvil and is provided with a segmental gear 11 which also meshes with the rack 9. The shaft 10 carries an arm 12 which supports the bottom member 13 of a second mold box having the box proper 14 telescopically assembled with the bottom member in the same manner as the box previously described.

At opposite sides of the machine unloading tables 15 and 16 respectively are arranged. After filling, a pallet plate is clamped to the top of the mold box and the mold box is then swung into inverted position and placed upon the corresponding unloading table where the charge is ejected, the mold box then returning empty to the anvil to receive another charge. In the arrangement shown the mold boxes are arranged to alternate in their operations so that while one is being filled the other is being emptied.

A screen 17 preferably surrounds the anvil to prevent portions of the mold charge from spattering as the charge enters the mold. Within the screen a supporting frame-work rises vertically to a considerable height above the anvil, said frame-work comprising the vertical posts 18 and suitable brace members connecting them.

At the upper ends the posts 18 are furnished with bearings 19 for parallel horizontal shafts 20 and 21. The upper ends of the posts are connected by girders 22 which support bearings 23 for a centrally disposed shaft 24. This shaft supports a clam-shell type hopper of inverted wedge shape com-

prising complementary members 25 and 26 which are hinged at their upper ends to the rod 24. Each of the complementary parts 25 and 26 of the hopper is provided with 5 one or more upstanding brackets 27 and the brackets carried by the respective members 25 and 26 are connected by a spring or springs 28 which tend to swing the opposite members of the hopper away from each 10 other so as to discharge any material held therein.

The brackets 27 are preferably continued downwardly and outwardly and are furnished with antifriction rollers 29. These 15 rollers bear against the peripheral surfaces of cams 30 and 31 mounted upon the shafts 20 and 21 respectively. Each cam comprises a concentric dwell portion 32, preferably of an extent greater than half of circumference of the cam, and an abrupt descent or active portion 33.

Normally the rollers 29 bear against the dwell portions 32 of the cams which are of such diameter as to hold the complementary 25 members 25 and 26 of the hopper in closed position so as to retain the charge which may be placed therein. When the cams are turned through a sufficient distance to bring the rollers opposite to the active portions 33 30 of the cams, the hopper parts are released and the weight of the material, assisted by the springs 28, causes the parts of the hopper to swing away from each other almost instantaneously, thus delivering the charge 35 substantially as a unit and permitting it to fall freely without restriction into the open mold box.

The shafts 20 and 21 are preferably turned in opposite directions simultaneously 40 by means of suitable connecting gears of which one is indicated at 34 in Fig. 2. The shafts are turned in properly timed relation to the operation of the mold box by any suitable means (not shown), for example, by crank and link connections to either or both of the shafts 7 and 10.

In Fig. 3 a modified arrangement is illustrated wherein the opposed parts 25^a and 26^a of the mold box are shown as provided 50 with the spring 28^a normally tending to separate them. In this instance the lower parts of the brackets 27^a are pivotally connected at 35 to links 36 which in turn are pivotally connected to piston rods 37 provided with pistons 38 working in pressure cylinders 39. These pressure cylinders are furnished with pressure fluid by means of pipes 40 which may be controlled by means of any suitable type of valve (not shown) 55 actuated by some convenient moving part of the machine.

While as herein disclosed the hopper is of two part construction it is evident that the release mechanism herein disclosed is 60 applicable to hoppers having a greater or

lesser number of moving parts and it is further to be understood that while the improved release mechanism is illustrated as embodied in a specific type of molding machine it is not in any manner limited to such 70 use but that it may be employed wherever it is desired to release a charge of material in a substantially instantaneous manner from a hopper or container.

I claim:

1. Apparatus of the class described comprising a hopper having a movable part tending to open to deliver a charge of material within it, and movable cam means normally holding said part in charge retaining position, said cam means comprising an abrupt descent permitting the sudden opening of said movable part of the hopper.

2. Apparatus of the class described comprising a charge delivery hopper of clamshell type comprising movable members pivotally supported adjacent to their upper ends, means tending to swing the lower ends of said members away from each other 90 to release a charge of material contained within the hopper, and cam means normally holding said member in charge retaining position, said cam means being constructed and arranged suddenly to release said 95 members.

3. Apparatus of the class described comprising a charge delivery hopper having opposed parts pivotally supported adjacent to their upper ends and tending to separate under the gravitational action of a charge of material in the hopper, and cams normally preventing such separation, said cams comprising abrupt descents permitting the sudden separation of said parts.

4. Apparatus of the class described comprising a charge delivery hopper having a movable element, spring means tending to move said element in one direction, and cam means normally preventing such movement, said cam means comprising an abrupt descent permitting the sudden movement of said member under the action of said spring.

5. Apparatus of the class described comprising a charge delivery hopper having a 115 movable member, spring means tending to move said member in one direction, and a cam for moving it in the other direction, said cam comprising a concentric or dwell portion extending throughout more than 120 one-half of its circumference and a radial depression or active portion constituting the remainder of its circumference.

6. Apparatus of the class described comprising a charge delivery hopper of inverted wedge shape having two substantially like parts hinged together at the top, arms projecting upwardly from the respective parts above their points of connection, a tension spring connecting said arms and 130

tending to swing the parts of the hopper away from each other, brackets carried by the respective parts and supporting anti-friction rollers, and a pair of cam members 5 arranged to engage the respective rollers and normally serving to hold the parts of the hopper in contact with each other.

7. Apparatus of the class described comprising a hopper of clam-shell type having 10 two substantially like members, a bracket projecting outwardly from each of said members, a pair of spaced horizontal shafts,

and a cam upon each of said shafts engageable with an element of the respective brackets, said cams each having a substantially concentric portion or dwell and a radial depression, the diameter of the concentric portions being such as normally to hold the members of the hopper in closed position.

Signed by me at Cambridge, Massachusetts, this 7th day of October, 1924.

CHARLES L. NORTON.
